UNITED STATES PATENT OFFICE.

HENRY KAGY, OF PHILADELPHIA, PENNSYLVANIA, ASSIGNOR TO THOMAS POTTER, SON & COMPANY, OF SAME PLACE.

DESIGN FOR OIL-CLOTH.

Specification forming part of Design No. 6,127, dated September 10, 1872.

To all whom it may concern:

Be it known that I, HENRY KAGY, of the city and county of Philadelphia, in the State of Pennsylvania, have invented and produced a new and original Design for an Oil-Cloth; and I do hereby declare the following to be a specification thereof.

The nature of my design is fully shown in the accompanying photographic illustration, which forms a part of this specification.

What I claim as my invention, and desire to secure by Letters Patent of the United States, is—

The design for an oil-cloth, substantially as shown.

HENRY KAGY.
